ANGORA ANKLET

Favorina Avondoglio, New York, N. Y.

Application November 23, 1936, Serial No. 112,324

1 Claim. (Cl. 2—239)

This invention relates to new and useful improvements in Angora anklets.

The invention has for an object the construction of Angora anklets in a manner so that the seams thereof are located in a position which will not hurt the feet. Furthermore, it is proposed to so arrange the seams that the anklets or the like may be partially or fully of Angora finish.

10 A further object of the invention is to so construct the anklets that they may be knitted from one color thread material or from threads of various colors.

15 Still further the invention proposes the construction in an Angora anklet of a foot portion having a sole section extending along the bottom and partially along both sides and continuing into a back section of the leg portion so that the anklet is continuous along the sole. This eliminates 20 seams in this region which are likely to irritate the foot.

25 Still further the invention contemplates arranging the foot portion with rectangular cutouts at the ankle areas, the rear edges of which are stretched down and attached to the bottom edges thereof, and the front edges of which are stretched out and attached to the stretched down section.

Still further it is proposed to use the same 30 material from which the anklets are knitted to attach together the edges mentioned in the previous paragraph.

Another object of the invention is the construction of an anklet as mentioned which is simple and durable and which may be manufactured and 35 sold at a reasonable cost.

For further comprehension of the invention and of the objects and advantages thereof, reference will be had to the following description and accompanying drawing, and to the appended 40 claim in which the various novel features of the invention are more particularly set forth.

In the accompanying drawing forming a material part of this disclosure:

45 Fig. 1 is a side elevational view of an anklet or the like constructed according to this invention.

Fig. 2 is a side elevational view of another anklet embodying the same invention.

Fig. 3 is a fragmentary enlarged detailed view 50 of a portion of the sock during the course of manufacture.

Fig. 4 is a fragmentary elevational view of a portion of an anklet constructed according to this invention but showing another embodiment.

55 Fig. 5 is a perspective view of the multi-yarn

or thread carrier used for knitting the anklets according to this invention.

In Fig. 1, an anklet or the like is shown which comprises a long leg portion 10 connected with a foot portion 11. This foot portion has a sole section 11a extending along the bottom and partially along the sides and continuing into a back section 10a of the said leg portion 10. At each side of the ankle area 12 of the anklet there is a seam between the points AB and CF. These 10 seams are at a location where they cannot possibly irritate the foot. They are so constructed as to make the anklet substantially form fitting on the foot.

In Fig. 3 a schematic view of an unfinished Angora anklet is shown so that the seams may be better understood. In this figure the knitting 11a represents the sole section of the foot portion. At the ankle area there is a rectangular opening 14 having the sides BA, AC and CD. The side BA is stretched and pulled down against the side AC, as indicated by the arcuate dotted line BC; along the line AC, these now adjacent edges are secured together by stitches 15 (see Fig. 1). The side DC, is then pulled across along the dotted line DF 20 until it reaches the side of the said pulled down edge BA. The side to which reference is had is indicated on the drawing by EB. The said adjacent edges are then secured together by the stitches 16 (see Fig. 1).

The anklet shown in Fig. 1 is partially of Angora. The leg portion 10 is completely Angora, and the Angora finish is extended over a section of the foot portion, namely, the vamp of the foot portion.

In Fig. 2 a modified form of anklet is shown constructed according to the same invention. This anklet has a short leg portion 10' having a top portion 10'' rolled down. This leg portion connects with the foot portion 11. This foot portion has a sole section 11a which continues into the back section 10a of the leg portion. The anklet is knitted so as to have seams at the ankle area 12. These seams extend between the points AB and FC. The construction is produced in the same manner as that described relative to Figs. 1 and 3. The anklet shown in Fig. 2 has a 100% Angora finish.

In Fig. 4 a portion of knitted material 16 is shown which is knitted with different colored threads. The knitting is arranged in stripes so that alternate stripes 16a are of one color threads, and the other stripes 16b of another color. This is merely shown to illustrate that the anklet may be knitted with different colored threads, by us- 55

ing multi-thread or yarn carriers 20, in the knitting machine. The carriers are provided with two or more vertical holes 21, to keep the yarn used in making the hose, spaced.

5 This improved anklet may also be made tubular, wholly of one piece of knitted Angora material without any seams, except the joining seam at the back of the leg portion of the anklet, according to this invention.

10 It is to be understood that this footwear may be either in the form of anklets, or in the form of socks, or other types of hose.

While I have illustrated and described the preferred embodiments of my invention, it is to be 15 understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:—

In a new article of manufacture, an anklet or the like hose, comprising a leg portion and a foot 5 portion, the foot portion having a sole section extending along the bottom and both sides thereof and continuing into a back section of said leg portion, and at each side of the ankle area having a rectangular opening, the material bounding 10 the rear end of said opening being stretched down and attached to the material bounding the bottom edge of said opening and the material bounding the front edge of said opening being stretched out and attached to an edge of the stretched down 15 section, said anklet having an Angora finish on the leg portion and on the vamp of the foot portion.
